COMBINATION ICE AND SNOW SCRAPER

Jon W. Hauser, St. Charles, Ill., assignor to National Brush Company, Aurora, Ill., a corporation of Illinois

Application July 30, 1957, Serial No. 47,151

Term of patent 14 years

(Cl. D9—6)

I claim:

The ornamental design for a combination ice and snow scraper, as shown.
